(57) **CLAIM**

The ornamental design for a liquid ejecting head unit, as shown and described.

DESCRIPTION

FIG. 1 is a perspective view of a liquid ejecting head unit showing our new design;

FIG. 2 is an exploded view thereof;

FIG. 3 is a top plan view thereof; and,

FIG. 4 is a cross-sectional view taken along line 4-4 in FIG. 3.

The broken lines in the drawings depict unclaimed portions of the liquid ejecting head unit and form no part of the claimed design.
